KEY FOR CYLINDER LOCKS

Bernard Stern, London, England

Application April 23, 1945, Serial No. 589,840
In Great Britain May 19, 1944

17 Claims. (Cl. 70—411)

1

This invention relates to keys for cylinder locks.

The kind of key to which the invention relates is that comprising a holder, a number of pins or bits which can be set in different positions by being displaced lengthwise in the holder, and locking means whereby the pins or bits can be locked in any positions in which they have been set or can be unlocked so as to be displaceable in the holder for adjustment purposes. Therefore, by properly adjusting the pins in accordance with the combination of the lock, a single key can be used for a very large number of locks; also, if the pins are set incorrectly after the key has been used, there is no need to place the key in a safe place because, owing to the large number of combinations possible, the danger of the correct combination for a particular lock being found by trial by an un-authorised person is almost infinitesimal.

The object of the present invention is to provide an improved key of the kind set forth in which any pin can be readily displaced without freeing or unlocking any other pins to such an extent that such other pins become liable to accidental displacement during the setting operation. A further object is to provide a key which can be easily manipulated in the dark or by blind persons and which is compact and of small size.

According to the invention, each pin is provided with individual means which, when the locking means is unlocked, retains it in its adjusted position against accidental shifting but permits it to be forcibly displaced for setting purposes. Therefore, when adjusting one of the pins, the possibility of others being displaced, for example by gravity, and thereby upsetting the combination is reduced to a minimum.

For retaining the pins in position when the locking means is unlocked, each pin may be formed with a number of teeth in the form of a rack with which an individual detent yieldingly engages. The locking means may consist of a displaceable sleeve or cap which, in the locked position, engages over the teeth on the pins and the detents, so as to prevent the latter from yielding and thereby locks the pins in the positions in which they have been set, and, in the unlocked position, is removed away from the detents, so that, although the detents still remain in engagement with the teeth on the pins, it is possible to adjust any pin by moving it forcibly in its longitudinal direction without releasing the detent of any other pin, since the detent only of the pin to be adjusted then yields and clicks over

the teeth of the rack in ratchet fashion making setting possible by sound or sense of touch.

In a preferred form of key in accordance with the invention, the holder comprises a plate provided on one or both sides with grooves or channels in which the pins are slidable lengthwise. At one end the pins are formed with teeth in the form of a rack with which spring detents attached to the plate engage. A sleeve or cap is slidable over the end of the plate and can be moved into a position in which it bears against the detents so as to hold them in engagement with the teeth on the pins and thereby fix the pins in position, or the sleeve or cap can be displaced into a position in which the detents are exposed and are able to yield so that the pins can be forcibly displaced in their grooves for setting purposes, but are held against accidental shifting.

The sleeve or cap is preferably provided with means whereby it is automatically locked when it is slid into the locking position in which it holds the detents in engagement with the teeth of the pins, the said means being releasable in order to enable the sleeve or cap to be withdrawn so as to unlock the pins for setting purposes.

The pins may be provided in their exposed faces with projecting lugs or the like so as to enable them to be readily grasped and the plate may be provided with numbered graduations corresponding to the number of teeth on the pins, so that the setting of each pin is readily visible. Each pin is also preferably numbered to enable its setting to be noted.

The pins provided with rack teeth can be moved only by steps, each step corresponding to the pitch of the teeth, which has the advantage that the pins can be set only in exactly pre-determined positions, and further the pins can be set in the dark or by a blind person since, when the pins are shifted, the clicking of the resilient detent over the teeth of the pins can be heard or felt and the number of steps can be counted.

The handle portion of the key is preferably curved, or provided with curved wings and the pins are so adjusted that when the handle is grasped between the thumb and forefinger of the right hand with the concave side against the thumb, which is the natural way of holding the key, the key will be the right way up for insertion in the lock. In the case of left-handed persons, if as is preferable, the operative end of the key is symmetrical, the pins can be reversed so that when the key is held in the manner described in the left hand, it will again be the right way up for insertion in the lock. The advantage is

thereby obtained that, when the key is grasped in the manner described, it is automatically held the right way up for insertion in the lock and it is unnecessary consciously to inspect or feel the position of the pins.

In order that the invention may be easily understood and readily carried into effect, a key constructed in accordance with the invention is illustrated, by way of example, in the accompanying drawings, in which

Fig. 1 is a side elevation of the key, partly in section;

Fig. 2 is a section on the line II—II of Fig. 1;

Fig. 3 is a section on the line III—III of Fig. 1;

Fig. 4 is a section on the line IV—IV of Fig. 1;

Fig. 5 is a perspective view of one of the pins or bits;

Fig. 6 is a perspective view of the means for locking the cap;

Fig. 7 is a section through a modified form of leaf spring detent; and

Fig. 8 is a perspective view thereof.

Referring to the drawings, the key comprises a handle portion 1 having a bow-shaped end 2. The handle portion 1 is in the form of a sleeve 3 in which a portion 4 for holding the pins or bits is a sliding fit. The portion 4 is in the form of a plate the thickness of which up to the point A in Figs. 1 and 2 is approximately equal to the internal width of the sleeve 3, while beyond this point, that is to the right-hand side of this point in Figs. 1 and 2, the thickness is reduced. The plate 4 is provided on each side with three grooves 5 which extend over the entire length of the plate. The central portions of the grooves, approximately between the right-hand end of the handle portion 1 and the point A in Figs. 1 and 2, are undercut, i. e. T-shaped in section as shown in Fig. 4 or may be dove-tailed. The rear portions 6 of the grooves which are enclosed by the handle 1 in Fig. 1 are not undercut but are slightly wider, their width being equal to that of the undercut of the central portions, and the portions of the grooves in the thinner portion of the plate 4 to the right of the point A in Fig. 1 are also not undercut and are of the same width as the central portions of the grooves above the undercut.

The bits or pins 7, all of which are identical, each consist of a bar composed of an outer rectangular portion 8, which is a sliding fit in the outer portion of the grooves 5, a central T-shaped portion 9 which is a sliding fit in the central T-shaped portion of the grooves 5 and a rear portion 10, the width of which is equal to that of the wider portion 6 of the grooves 5. The upper surface of the rear portion 10 is formed with nine teeth 11 whereby ten indentations or tooth gaps are formed. The height of the portions 8 and 9 of the pins is such that, when the pins are slid into the grooves 5, the upper surfaces of these portions are flush with the surface of the thicker portion of the plate 4, as shown in Fig. 4, while in the thinner portion of the plate to the right of the point A the pins project out of the grooves as shown in Fig. 2. The height of the teeth 11 is such that the tips of the teeth are slightly below the surface of the portions 8 and 9, so that a small space is left between the tips of the teeth and the inner surface of the sleeve 3 when inserted over the plate 4 and the ends of the pins therein. Each pin is formed with a lug or projection 12 which acts as a means for setting the pins and is marked with a numeral 13. In the key illustrated in which there are six pins, each

pin being marked with a different numeral from 1 to 6. In Fig. 5 the portion 9 of the pin 7 is shown of dovetail form for engagement with a groove 5 having a similarly shaped central portion. When the central portions of the grooves 5, however, are T-shaped as shown in Fig. 4 the portions 9 of the pins 7 will, of course, also be T-shaped.

The thinner end of the plate 4 is marked on each side of the three grooves 5 with graduations 14, 15, 16 and 17. The graduations 14 and 16 are aligned, while the graduations 15 and 17, which are also aligned, are half-way between the graduations 14 and 16. The distance between the graduations of each of the four series is equal to twice the pitch of the teeth 11. The spaces between the graduations 15 are marked with the even numbers 0-8 and the spaces between the graduations 16 with the odd numbers 1-9. When in their innermost positions the outer ends of the pins 7 are in line with the first graduation of the graduations 14 and 16, i. e. opposite the numeral 0, as shown in Fig. 1 in the case of the bit identified by the number 6. When moved from their innermost positions through a distance equal to the pitch of the teeth 11 the outer ends of the pins are in line with the first graduation of the graduations 15 and 17 and when moved again through a distance equal to the pitch of one tooth they are in line with the second graduation of the graduations 14 and 16, i. e. opposite the numeral 2, and so on.

In the space between the teeth 11 and the sleeve 3 there is fixed to the plate 4 by means of rivets 18 a leaf spring 19 which is separated by two slots 20 into three sections, each of which is provided with a detent 21, which is formed by bending the end of the spring inwards and engages in the gaps between the teeth 11. When the sleeve 1 is in the position illustrated in Fig. 1 the detents 21 are held in engagement with the teeth 11 and the pins 7 cannot be shifted. When the sleeve 1 is shifted to the left in Fig. 1 so that the spring 19 is exposed, it is possible to set the pins 7 into any desired position by pushing on the lugs 12, since the detents are able to yield and click over the teeth 11 as the pins are moved. The movement of the sleeve 1 relative to the plate 4 is limited by means of screws or the like 22 which engage in grooves in the side edges of the plate 4.

It will be seen that each pin can only be moved in steps, each step corresponding to the pitch of the teeth 11, since, as a pin is displaced, the detent 21 clicks ratchetwise over the teeth 11. The graduations 14, 15, 16 and 17, are, of course, so arranged that the end of each pin, when in any of the ten positions which it can occupy, is exactly opposite one of the graduations, for example, the uppermost pin in Fig. 1 is opposite the second graduation of the graduations 14, as indicated by the numeral 2 between the graduations 15, denoting that this pin has been displaced by two steps or twice the pitch of the teeth 11 from its innermost position.

The sleeve 1 is also provided with locking means which ensures that the sleeve is normally locked in the position shown in Fig. 1 in which the pins 7 are fixed in position. For this purpose each of the springs 19 is provided with a rearward extension 23 having a detent 24 formed by bending the spring inwardly, and a detent-engaging member 25 is fitted in a space between the end of the plate 4 and the end of the sleeve 1. The member 25 is formed with a circular boss 26 which is turnably fitted in an aperture in the end

of the sleeve 1 and is fitted with a milled head 27 which is fixed on a square extension 28 of the boss 26. The member 25 at the end adjacent the end of the sleeve 1 is of the shape shown in Fig. 3 and is provided on opposite sides with an outwardly extending step 29 over which the detents 24 normally engage, as shown in Fig. 2. The undersurface of the step 29 is inclined as shown at 30. A leaf-spring 31 which passes through a slot 32 in the detent and of which the ends bear against opposite sides of the casing 1 normally holds the member 25 in a position in which the detents 24 are in engagement with the steps 29, so that the sleeve 1 cannot be withdrawn. By turning the milled head 27, however, the detents 24 are disengaged from the steps against the action of the spring 31 and the sleeve 1 is free to be withdrawn to an extent which is limited by the screws 22 abutting against the left-hand ends (in Figs. 1 and 2) of the grooves in the edges of the plate 4. The springs 19 are thereby exposed and the detents 21 are able to yield so as to allow the pins to be set. After the pins have been adjusted, the sleeve 1 is slid back to the position illustrated in which the pins are locked in the positions in which they have been set. When the sleeve 1 is slid back the detents 24 engage the inclined undersurfaces 30 of the steps 29 and thereby automatically rotate the member 25 through a small angle against the action of the spring 31 until the detents 24 are level with the surfaces of the steps 29, whereupon the member 25 is turned back again by its spring 31 until it is in the position shown in Fig. 3 in which the detents 24 engage over the steps 29, and the sleeve is locked in position. The sleeve 1 is formed with curved wings as shown in Fig. 1, so that the key will naturally be held the right way up for insertion in the lock, as described previously.

It will be noted that whereas a longitudinal movement of the handle portion relative to the plate 4 can effect the locking of the pins, an additional movement, namely rotation of the head 27, is necessary to effect the unlocking of the pins. Such additional movement is not one which would normally be made in handling the key or inserting it in and withdrawing it from the lock, and consequently the pins cannot accidentally become unlocked, for example owing to the key sticking in the lock, when the key is used in the normal manner.

Figs. 7 and 8 illustrate an alternative form of the leaf spring 19 which carries the detents 21.

As shown in these figures, the sides 19' of each of the three springs into which the spring 19 is divided by the slots 20 are bent towards the sleeve 3, the lines of bending being inclined, as shown in Fig. 7, to the sides of the springs. A tooth 21 is thus indented or pressed at or near the end of each of the individual springs, the tooth projecting in the opposite direction to the bent portions 19'. The action is substantially the same as that previously described, but this construction has the advantage that, owing to the bent portions 19', the teeth 21 are held firmly in the tooth gaps of the pins so that the latter are firmly held even if there should be a slight amount of play between the outer surface of the spring 19 and the inner surface of the sleeve 3.

I claim:

1. An adjustable key for cylinder locks comprising a holder, a plurality of pins displaceable lengthwise in said holder, means whereby said pins may be locked in any positions in which

they have been set and may be unlocked to enable them to be displaced and means whereby, when said pins are unlocked, each pin is individually retained in its adjusted position against accidental shifting but may be forcibly displaced in either direction for setting purposes.

2. An adjustable key for cylinder locks comprising a holder, a plurality of pins displaceable lengthwise in said holder, a plurality of teeth on each of said pins, a plurality of detents attached to said holder, each of said detents being engageable with the teeth of one of said pins and releasable means whereby said detents may either be held in engagement with the teeth of said pins or may be released to such an extent that the pins may be forcibly displaced in either direction for setting purposes but are nevertheless retained in their adjusted positions against accidental shifting.

3. An adjustable key for cylinder locks comprising a holder, a plurality of pins displaceable lengthwise in said holder, a plurality of teeth on each of said pins, a plurality of resilient detents attached to said holder and each engageable with the teeth of one of said pins and releasable means whereby said detents may either be held in engagement with the teeth of said pins or may be released to such an extent that the pins may be forcibly displaced in either direction for setting purposes but are nevertheless retained in their adjusted positions against accidental shifting.

4. An adjustable key for cylinder locks comprising a holder, a plurality of pins displaceable lengthwise in said holder, a plurality of teeth on each of said pins, a plurality of detents attached to said holder and each engageable with the teeth of one of the said pins, a displaceable sleeve on said holder surrounding said detents, said sleeve being movable into two positions in one of which said detents are held in engagement with said teeth and in the other of which said detents are free to yield so that said pins can be moved, and means whereby said sleeve is automatically locked when moved into the said first-mentioned position.

5. An adjustable key as claimed in claim 4, in which the means for locking said sleeve comprises a detent member pivoted in the sleeve and a detent attached to the holder.

6. An adjustable key for cylinder locks comprising a holder, a plurality of pins displaceable lengthwise in said holder, means comprising a member displaceable on said holder whereby said pins may be locked in the position in which they have been set and may be unlocked to enable them to be displaced, means whereby each pin, when unlocked, is individually retained in its adjusted position against accidental shifting, and means whereby said displaceable member is automatically locked when moved into the position in which said pins are locked.

7. An adjustable key for cylinder locks comprising a plate, grooves in said plate, pins slidable in said grooves, teeth formed on one end of each of said pins, detents attached to said plate and each resiliently engaging the teeth of one of said pins, and a sleeve engaging over the end of said plate and detents, said sleeve being movable into two positions in one of which said detents are held in engagement with said teeth, and in the other of which said detents are free to yield so that said pins can be shifted in said grooves.

8. An adjustable key for cylinder locks comprising a plate, grooves in said plate, pins slidable

in said grooves, teeth formed on one end of each of said pins, leaf springs attached to said plate, teeth on said springs engaging the teeth on each of said pins, and a sleeve engaging over the end of said plate and said leaf springs, said sleeve being movable into two positions in one of which said teeth on said springs are held in engagement with the teeth on said pins and in the other of which said teeth on said springs are free to yield so that said pins can be shifted in said grooves.

9. An adjustable key for cylinder locks comprising a holder, a plurality of pins displaceable lengthwise in said holder, a plurality of teeth on one end of each of said pins, a plurality of detents attached to said holder and each engageable with the teeth of one of said pins, a sleeve displaceable on said holder and surrounding said detents, said sleeve being movable into two positions in one of which said detents are held in engagement with said teeth, and in the other of which said detents are free to yield so that said pins can be shifted, a detent pivoted in the end of said sleeve, and a cooperating detent member attached to said plate and automatically engaged when said sleeve is moved into said first-mentioned position.

10. An adjustable key as claimed in claim 9, in which said detents engaging the teeth of the pins and said detent member attached to said plate are constituted on each side of the plate by a single leaf spring.

11. An adjustable key as claimed in claim 9, in which said detent pivoted in the end of said sleeve is connected to an operating member disposed outside the sleeve, so that said pivoted detent can be released by actuating said operating member.

12. An adjustable key for cylinder locks comprising a holder, a plurality of pins displaceable lengthwise in said holder, means including a sleeve displaceable on said member whereby said pins may be locked in any positions in which they have been set and may be unlocked to enable them to be displaced, means whereby, when said pins are unlocked, each pin is individually retained in its adjusted position against accidental shifting but may be forcibly displaced for setting purposes, a detent member pivotally mounted within said sleeve, a detent attached to said holder and adapted to be engaged by said detent member when said pins are locked by said sleeve, and means located outside said sleeve whereby said detent member can be released from said detent.

13. An adjustable key for cylinder locks comprising a holder, a plurality of pins displaceable lengthwise in said holder, a plurality of teeth on each of said pins, a plurality of detents each attached to said holder and engageable with the teeth of one of said pins, a displaceable sleeve on said holder surrounding said detents, said sleeve being movable into two positions in one of which said detents are held in engagement with said teeth and in the other of which said detents are free to yield so that said pins can be

shifted, and a curved handle portion forming part of said sleeve.

14. An adjustable key for cylinder locks comprising a holder, a plurality of pins displaceable lengthwise in said holder, a plurality of teeth on one end of each of said pins, a plurality of detents attached to said holder and each engageable with the teeth of one of said pins, a sleeve displaceable on said holder and surrounding said detents, said sleeve being movable into two positions in one of which said detents are held in engagement with said teeth and in the other of which said detents are free to yield so that said pins can be shifted in said grooves, a detent pivoted in the end of said sleeve, and a cooperating detent member which is attached to said plate and is automatically engaged when said sleeve is moved into said first-mentioned position, a handle portion on said sleeve, an aperture in said handle portion and operating means whereby said detent may be rotated about its pivot disposed in said aperture.

15. An adjustable key for cylinder locks comprising a plate, grooves in said plate, said plate and grooves being symmetrically formed, pins in said grooves, teeth formed on one end of each of said pins, detents attached to said plate and resiliently engaging said teeth, a sleeve engaging over the end of said plate and detents, said sleeve being movable into two positions in one of which said detents are held in engagement with said teeth, and in the other of which said detents are free to yield so that said pins can be shifted in said grooves.

16. An adjustable key for cylinder locks comprising a holder, a plurality of pins displaceable lengthwise in said holder, a plurality of teeth on each of said pins, a plurality of resilient detents attached to said holder and each engageable with the teeth of one of said pins, a sleeve displaceable in the longitudinal direction of said pins surrounding said detents and being movable into two positions in one of which said detents are held in engagement with said teeth and in the other of which said detents are free to yield, means whereby said sleeve is automatically locked when moved into said first-mentioned position and means operable by a movement transverse to the longitudinal direction of said pins whereby said locking means may be unlocked.

17. An adjustable key for cylinder locks as claimed in claim 8, wherein said leaf springs comprise portions bent in a direction towards said sleeve, so that the teeth on said springs are pressed by said sleeve into the gaps between the teeth on said springs.
